UNITED STATES PATENT OFFICE.

NATHAN KASDAN, OF BRONX, AND DANIEL POLLACK, OF BROOKLYN, NEW YORK, ASSIGNEES TO MAJESTIC MACHINE & TOOL CO., INC., OF NEW YORK, N. Y., A CORPORATION OF NEW YORK.

VANITY BOX.

Application filed December 28, 1923. Serial No. 683,109.

The invention relates to improvements in vanity-boxes of the class having a body-portion, a cover-portion hinged thereto and a mirror, the body and cover portions being provided with means for holding powder and rouge compacts and their respective puffs or pads.

In accordance with our invention we provide a novel insert or attachment to be applied within the body or cover portion of the box and affording a compartment for a compact, and we also provide novel means for holding compacts in place, and the mirror according to our invention, is pivoted at one edge to one edge portion of said insert or attachment in a manner permitting the same to lie close against said insert or attachment when the box is closed and to be turned outwardly from the same when the box is open, the mirror when turned outwardly on its pivot exposing the compartment in the insert or attachment it normally covers and passing into convenient position for use as a mirror.

The invention will be fully understood from the detailed description hereinafter presented, reference being had to the accompanying drawings, in which:

Fig. 1 is a central vertical section through a vanity-box embodying our invention, the box being shown in open position, with the pivoted mirror turned outwardly and the powder and rouge compartment exposed, and the section being on the dotted line 1—1 of Fig. 2;

Fig. 2 is a front perspective view of the same, taken from the right hand side of Fig. 1;

Fig. 3 is a central vertical section through the box, the box being shown in closed position;

Fig. 4 is a top view of the bottom member of the box, shown open, a fragment of the top member of the box being also illustrated;

Fig. 5 is a vertical transverse section taken on the dotted line 5—5 of Fig. 2;

Fig. 6 is a vertical section, on an enlarged scale, through an edge portion of the box, taken on the dotted line 6—6 of Fig. 4;

Fig. 7 is a horizontal section, on an enlarged scale, through an edge portion of the box, taken on the dotted line 7—7 of Fig. 1;

Fig. 8 is a top view, partly broken away,

of a modified construction of box embodying our invention, the box being shown in open position and the modification consisting mainly in pivoting the mirror on one lateral side portion of the insert for the cover-member and in locating the compartment for the rouge compact centrally of said insert;

Fig. 9 is a vertical section through a portion of the same, taken on the dotted line 9—9 of Fig. 8;

Fig. 10 is a bottom view of a portion of the mirror frame shown in Figs. 8 and 9, Fig. 10 being presented to illustrate the snap-fastener member formed integrally with said frame;

Fig. 11 is a top view, partly broken away, of a further modified construction of box embodying our invention, the mirror in this instance being pivoted to an insert arranged in the bottom of the box, and the box being shown in open position;

Fig. 12 is a vertical section on a larger scale and partly broken away, of the same, taken on the dotted line 12—12 of Fig. 11, and

Fig. 13 is a vertical section through a portion of the same, taken on the dotted line 13—13 of Fig. 12.

In the drawings, referring to Figs. 1 to 7 inclusive, 15, 16 respectively designate the two main members of the box and either of these members may be regarded as the body portion or cover portion of the box, since said members in exterior appearance harmonize with each other and both are substantially equal in size. For purposes of description the member 15 may be regarded as the body member and the member 16 as the cover. The body 15 and cover 16 are connected together by a suitable hinge 17, and the body 15 is equipped with a suitable push-button latch 18 to engage a shoulder 19 formed in the rim 20 of the cover 16, for the purpose of securing the box-members in closed position. The rim 21 of the body 15 matches the rim 20 of the cover 16 and said rims pass into abutting relation to each other when the box is closed, thus leaving no projecting shoulder along the periphery of the box. The bottom of the body 15 is concaved to increase the capacity of said body, and the top of the cover 16 is likewise concaved to increase the capacity of said

cover. The main exterior surfaces of the bottom of the body 15 and top of the cover 16 are convex and harmonize with each other. The bottom of the body 15 is formed with a flat edge portion 22, and the top of the cover 16 is formed with a corresponding flat edge portion 23, which portions 22, 23 constitute shoulders.

Within the body 15 is placed a powder compact 24 carried by a plate 25 which fits the concave bottom of the body 15 and is formed with a plurality of laterally projecting edge tabs 26 (Figs. 4 and 6) to rest upon the shoulder 22. The rim 21 of the body 15 is formed with a plurality of indentations 27 which project inwardly above the shoulder 22 and serve, with the flanges 26, to lock the plate 25 in position. When the powder compact is placed within the body 15 it will be initially positioned to locate the flanges 26 between but adjacent to the indentations or projections 27, and then the compact will be turned to carry the flanges 26 below said indentations or projections 27 or to the position shown in Figs. 4 and 6. When the powder compact 24 has been used up, the plate 25 will be turned to carry its flanges 26 from below the indentations or projections 27, and thereupon the plate 25 may be removed and the body 15 replenished with a new compact. We regard the manner just described of securing the powder compact in and releasing the plate 25 from the body 15 as a desirable feature of our invention.

The cover 16 receives an insert or attachment 28 formed of one integral piece of sheet metal and comprising a face-plate 29 and a peripheral annular rim 30 which closely fits within the rim 20 of said cover and is detachably secured in position by indented projections 31 in the rim 20 (Fig. 5) entering corresponding indentations 32 in the rim 30. When the insert 28 is in position, the free edge of the rim 30 engages the shoulder 23. The rim 30 is cut away at the latch 18 and flanges 33 (Fig. 7) of the hinge 17 so as to pass by said projecting features.

The metal of the plate 29 is flanged inwardly, as at 34, to form a circular compartment for a rouge compact 35 and its puff or pad 36, and preferably the flange 34 has spring fingers 37 slit from it to engage the edges of the plate carrying the compact 35 and releasably hold said plate in position, the free ends of said fingers being angularly bent inwardly to extend over the edge of said plate, as shown in Fig. 1. At one edge of the compartment for the rouge compact 35 a lip 38 is formed on the plate 29 to extend over one edge of said compartment and the puff 36 and aid in retaining the puff against accidental displacement.

The compartment or chamber for the rouge compact 35 may be made of consider-

able depth by reason of the concavity of the top of the cover 16, as shown in Figs. 3 and 5, and said compartment or chamber is preferably located eccentrically of the plate 29 so as to provide space for a chamber 39 to receive a lip or other stick holder 40 of customary type. The chamber 39 is formed by flanging the metal of the plate 29 inwardly, as shown in Fig. 5, and at one side of said chamber is formed a finger space 41 to facilitate the withdrawal of the holder 40 from the chamber 39. The end portions of the holder 40 may rest upon the inner surfaces of the top of the cover 16, when the cover is open, since said end portions will be located within the deeper concave portions of said cover.

The mirror 42 is secured upon a plate 43 and this plate is pivoted near one edge to the face-plate 29 near one edge thereof, as shown in Fig. 1, so as to be turned to lie against the plate 29, as shown in Figs. 3 and 5, or to extend therefrom for use, as shown in Figs. 1 and 2. The plate 43 may be pivoted to the plate 29 in various ways, but in Figs. 1 and 3 we show the pivoting means as an eyelet 44 formed from the plate 43 and engaged in a flanged aperture in the plate 29. The mirror and its plate 43 always remain parallel with the plate 29, and when the mirror is turned to lie against the plate 29, the plate 43 closes the compartment for the rouge compact and also the chamber for the stick-holder 40 and retains said compact and holder in place. The mirror will preferably be pivoted or swiveled to the plate 29 near that portion of the cover 16 opposite to the hinge 17, so that when the box is opened the mirror may be turned outwardly in line with the body 15 and cover 16, as shown in Figs. 1 and 2. When it is only desired to use the powder compact 24, the box may be opened and the mirror left in its normal position facing the user.

When the mirror is turned upon the plate 29 and the box is closed, the mirror forms a partition between the body 15 and cover 16 and closes the compartments in both of said members.

The insert 28, with the mirror swivled thereto, constitutes an attachment which may be pushed into the cover 16.

The insert 28 in addition to its other conveniences, normally extends outwardly beyond the free edge of the rim 20 of the cover 16, as shown in Figs. 2 and 3, thereby leaving an annular shoulder which projects into the body 15 when the box is closed, as shown in Fig. 3, this shoulder being of importance in securing a tight closure and permitting the rims 20, 21 of the cover and body to pass into abutting relation to each other when the box is closed and leave the box with a plain peripheral surface.

In the modification shown in Figs. 8, 9

and 10, the body 15 and cover 16 are of the same construction that we have already described with reference to Figs. 1 to 7 inclusive, and the insert or attachment 45 is the same as the insert 28 except that the compartment 46 for the rouge compact 47 is formed concentrically of the face-plate 48 and no provision is made for a lip-stick holder. In Figs. 8, 9 and 10 the mirror 49 and its plate 50 are swiveled to the face-plate 48 at one lateral side portion thereof instead of at a point farthest from the hinge 17, but in other respects the mirror 49 and plate 50 perform all the duties of the mirror 42 and plate 43 shown in Fig. 1. In Figs. 8, 9 and 10, we connect the mirror-plate 50 with the face-plate 48 by means of a snap-fastener head 51 pushed down through an aperture in the plate 48, instead of by means of the eyelet 44 shown in Fig. 1. The modification shown in Figs. 8, 9 and 10 will be fully understood without further detailed explanation.

In the modification shown in Figs. 11, 12 and 13, the body 52 is of the same construction as the body 15 of Fig. 1, but in Figs. 11, 12 and 13 we show said body as having an insert 53 closely fitting the rim 54 thereof and comprising a face plate 55, an outer depending annular rim portion or flange 56 and an inner depending annular flange 57 formed with spring-fingers 58 for retaining the powder compact 59 in the body 52. The insert 53 extends above the free edge of the rim 54 of the body 52, thereby creating an annular exposed shoulder which we number 60, to enter the cover 61 when the box is closed, thereby, as with the construction shown in Fig. 2, ensuring a tight closure and a plain peripheral surface on the box. The insert 53 is secured within the body 52 by indentations 62 in the rim 54 entering correspondingly indentations 63 in the flange 56, as shown in Fig. 13. The mirror 64 is carried by a plate 65 and this plate is swiveled to one side portion of the top of the insert 53 by means of an eyelet 66 formed out of the metal of the plate and engaged with a flanged aperture in the insert, as will readily be understood on reference to Figs. 11 and 12.

We present Figs. 11, 12 and 13 to indicate that the insert to which the mirror is swiveled may be applied to the body of the box as well as to the cover of the box, but by preference the insert will be applied to the cover, as shown in Figs. 1 and 8.

What we claim as our invention and desire to secure by Letters Patent, is:

1. A vanity-box comprising a body member having a rim, a cover member having a rim, an insert having a rim closely fitting within the rim of one of said members and the insert-rim projecting outwardly beyond the free edge thereof to enter the other

member when the box is closed with said body and cover rims in abutting relation, and a mirror swiveled near one edge to said insert and adapted to be turned in its own plane outwardly from the box and inwardly against said insert, said mirror serving as a partition between the body and cover chambers when the box is closed.

2. A vanity-box comprising a body-member having a rim, a cover member having a rim, an insert comprising a face-plate and a marginal flange closely fitting within the rim of one of said members and which plate is close to the edge of the latter rim, and a mirror pivoted near one edge against an edge portion of said face-plate so as to have a swiveling movement in its own plane and adapted to lie against said plate when the box is closed and to be swiveled outwardly therefrom to expose said plate when the box is open, said mirror serving as a partition between the body and cover chambers when the box is closed, and said insert containing a compartment for a toilet compact and its puff.

3. A vanity-box comprising a body-member having a rim, a cover member having a rim, an insert comprising a face-plate and a marginal flange closely fitting within the rim of one of said members and which plate is close to the edge of the latter rim, and a mirror pivoted near one edge against an edge portion of said face-plate so as to have a swiveling movement in its own plane and adapted to lie against said plate when the box is closed and to be swiveled outwardly therefrom to expose said plate when the box is open, the other of said members being adapted to receive a toilet compact and its puff, said mirror serving as a partition between the body and cover chambers when the box is closed, and said insert containing a compartment for a toilet compact and its puff.

4. A vanity-box comprising a body-member having a rim, a cover member having a rim, an insert comprising a face-plate and a marginal flange closely fitting within the rim of one of said members and which plate is close to the edge of the latter rim, and a mirror pivoted near one edge against an edge portion of said face-plate so as to have a swiveling movement in its own plane and adapted to lie against said plate when the box is closed and to be swiveled outwardly therefrom to expose said plate when the box is open, said mirror serving as a partition between the body and cover chambers when the box is closed, and said insert having an interior portion thereof flanged downwardly to form a compartment for a toilet compact and its puff and a portion thereof extended over one edge of said compartment to aid in retaining the puff in place.

5. A vanity-box comprising a body member having a rim, a cover member having a rim, an insert comprising a face-plate and a marginal flange closely fitting within the
5 rim of one of said members and which plate is close to the edge of the latter rim, and a mirror pivoted near one edge against an edge portion of said face-plate so as to have a swiveling movement in its own plane and
10 adapted to lie against said plate when the box is closed and to be swiveled outwardly therefrom to expose said plate when the box is open, the other of said members being adapted to receive a toilet compact and its
15 puff, said mirror serving as a partition between the body and cover chambers when the box is closed, and said insert containing an eccentrically disposed compartment for a toilet compact and its puff adjacent there-
20 to a compartment for a toilet-stick holder.
6. A vanity-box comprising body and cover members hinged together at one edge and provided with a spring latch at the opposite edge, one of said members being
25 adapted to receive a powder compact and

its carrying plate and having indentations in its sides to extend over the edges of said plate to hold the same in position, said plate being cut away at its edge portions to pass by said indentations and adapted then to be turned to carry solid portions of its edge below said indentations.

7. In a vanity case, body and lid members, a mirror carrying plate having a portion of its stock deflected to form a pivot-pin, said pin being pivotally mounted in one of said members, whereby the mirror may be swung out of the case.

8. In a vanity case, body and lid members, a mirror carrying plate having a portion of its stock cut and downwardly upset to form a pivot pin, said pin being pivotally mounted in one of said members, whereby the mirror may be swung out of the case.

Signed at New York city, in the county 45
and State of New York, this 27th day of
December, 1923.

NATHAN KASDAN.
